UNITED STATES PATENT OFFICE

FREDERICK W. GRIEVE, OF CRESTWOOD, NEW YORK

GOLF CLUB

Application filed April 11, 1930. Serial No. 443,311.

My invention relates to golf clubs and has special reference to golf clubs of the spoon and brassie type.

One of the objects of my invention is to provide a spoon or similar golf club which, although of standard size, weight, balance, and set of the club head in addressing the ball, is so constructed that a ball may be fairly struck from a depression or other bad lie where ordinarily an iron would be required.

Another object of my invention is to provide a golf club of the standard spoon and brassie type in which the club head is capable of more easily, smoothly and accurately cutting through the turf in striking the ball than clubs of this type heretofore in general use.

The several features of my invention, whereby the above mentioned and other objects may be attained, will be readily understood from the following description and accompanying drawing, in which:

Figure 1 is a front elevation of a club head embodying the features of my invention in their preferred form;

Figs. 2 and 3 are respectively bottom plan and rear views of the same; and

Fig. 4 is a sectional view taken on the line 4-4 of Fig. 1.

My improved club head is preferably made of wood and of standard size, weight, balance, and set in addressing a ball. The club head is provided with the usual striking face 2 and beveled toe and heel 4 and 6, respectively.

In accordance with my invention a substantial T-shaped metal plate 8, preferably of brass, is set into the sole of the club head and secured in place by screws 10 extending through apertures in the end portions of the cross-bar 11 of the plate, and screws 12 extending through apertures at the front and rear portions of the plate on the center line 45 of the club head, the several screws being screwed into the head. The cross-bar portion 11 of the plate extends over the forward portion of the bottom side of the head with the central portion of its forward edge flush 50 with the striking face 2 and the remaining

portions of its forward edge flush with the curved surfaces adjacent the ends of the striking face. The member 14 of the plate is arranged horizontally and extends centrally of the club head and striking face. 55 The forward portion 11 of the sole plate is convexedly curved at a sharper angle than corresponding forward portions of club heads heretofore in general use, and its rear edge portions 15 are beveled off slightly as shown. The member 14 of the sole plate also is convexedly curved as shown. The portions 16 of the bottom side of the head not covered by the sole plate are slabbed or chamfered off upwardly and rearwardly from the rear edges of the forward portion 11 of the plate, and upwardly and outwardly from the edges of the central portion 14 of the plate as shown, said beveled off portions 16 gradually merging into said edges of the 70 sole plate.

With this construction of spoon or similar club head, it has been found that in striking the ball the head digs or cuts through the turf easily, smoothly and accurately. 75 The convexedly curved front edge of the sole plate easily cuts into the turf, and as the head carries through the portion 11 and the member 14 of the sole plate offer but little resistance, the remaining portions 16 of the 80 bottom surface of the head sloping sufficiently to clear the ground cut by the front edge of the sole plate. Moreover, the central member 14 of the sole plate tends to maintain the travel of the head in a straight line as it engages the ground in striking the ball. 85

Owing to the construction of the bottom surface of the club head with the ample clearances provided by the sloping portions 16, the forward or cutting edge portion of the sole 90 plate may be made with a sharper convex curvature and thus may more easily cut deeper into the turf than is practicable with the club heads heretofore in general use.

The sole plate is preferably made of relatively heavy brass plate, substantially one-eighth inch in thickness, and because of the arrangement of the member 14 thereof centrally of the club head relatively little lead weight 18 is required. To apply this weight 100

- 18, the sole plate may be first secured on the club head and then the rear screw 12 is removed. The head may then be centrally bored and said screw replaced, and then the necessary amount of lead weight 18 may be applied by pouring molten lead into the bore. This lead surrounds the portion of the screw extending through the bore so that when the lead solidifies it is securely held in place.
- 10 The central member 14 of the sole plate and also the weight 18 concentrates the weight of the head in a vertical plane extending through the center of the striking face where it is required to secure proper balance.
- 15 It will be apparent that my improved club head may be made of the standard size, weight, and balance and the shape of the sole plate is such as to give the club the proper set in addressing the ball.
- 20 As will be evident to those skilled in the art, my invention permits various modifications without departing from the spirit thereof or the scope of the appended claims.

What I claim is:

- 25 1. A golf club of the class described having a substantially T-shaped sole plate set into the bottom side of its head with the cross-bar of the plate forming the forward part of said bottom side and the other part 30 of the plate extending centrally transversely of the head and arranged substantially horizontally, the remaining portions of the bottom side of the head being inclined upwardly and rearwardly from said cross-bar and upwardly and outwardly from said central part 35 of the sole plate.
2. A golf club of the class described having a substantially T-shaped sole plate set into the bottom side of its head with the 40 cross-bar of the plate forming the forward part of said bottom side and the other part of the plate extending centrally transversely of the head and arranged substantially horizontally, the remaining portions of the bottom side of the head being cut away to provide ground clearance.
3. A golf club of the spoon and brassie type having the forward portion of the sole of its head convexedly curved longitudinally 50 thereof, the central portion of its sole extending from said forward portion rearwardly being arranged horizontally and substantially flush with the forward portion, and the remaining portions of its sole inclined upwardly and outwardly from said central portion and upwardly and rearwardly from said forward portion.
4. A golf club of the spoon and brassie type having the forward portion of the sole 55 of its head convexedly curved longitudinally thereof, the central portion of its sole extending from said forward portion rearwardly being arranged horizontally, substantially flush with the forward portion and convex- 60 edly formed transversely thereof, said for-

ward and central portions of the sole together being of substantially T-form, and the remaining portions of its sole cut away to provide ground clearance above said forward and central portions.

In testimony whereof, I have signed my name to this specification.

FREDERICK W. GRIEVE.
